ARRANGEMENT OF THE DELIVERY OF THE
WARP THREADS TO CIRCULAR WEAVING
LOOMSJean Dunod, Paris, France, assignor to Qualitex-
Societe Dunod & Cie, Paris, France, a corpo-
ration of France

Application July 26, 1951, Serial No. 238,673

Claims priority, application France July 27, 1950

5 Claims. (Cl. 139—13)

1

The invention relates to an arrangement of the delivery of the warp threads to a circular weaving loom in which the warp threads, wound on six beams or cylinders disposed circularly at the base of the loom along the sides of a regular hexagon, pass thence over a thread-carrying bar where curvature permits of a geometric transition, without constraint, from the plane surface formed by the assemblage of warp threads leaving each beam to the cylindrical weaving surface, the threads being then passed into the eyes of the heddles and between the teeth of the circular reed.

One object of the invention is to arrange the beams carrying the warp threads in a convenient and reliable manner and to permit of their easy changing.

Another object is to brake these beams in order to ensure the regular unwinding of the thread.

Another object is to provide an arrangement for giving warning in the case of breakage of a warp thread.

Another object of the invention is to produce a thread-carrying bar of appropriate shape.

In the annexed drawings, there is represented diagrammatically and by way of example one mode of carrying out the invention.

Figure 1 is a plan showing the arrangement of warp thread cylinders or beams.

Figure 2 shows in elevation a stool mounted upon the platform constituted by the lower frame and the cylinder-carrying carriages.

Figure 3 shows in elevation the braking system for a cylinder.

Figure 4 shows in perspective a broken warp detector arrangement.

Figures 5—10 and 10a show the principle of the transformation without constraint of the flat sheet of warp threads into a cylindrical sheet.

Figure 11 shows in elevation one half of a loom in which the invention is embodied.

Figure 12 shows in vertical section the other half of the loom.

Referring first to Figures 1 and 2 and accessorially to Figures 11 and 12, it will be seen from Figure 1 that the lower frame is composed of six iron bars 1 of I-section equidistant and arranged according to radii of a circle. This frame has for its centre the centre 158 of the weaving loom. Upon each of these bars and towards their outer extremity there is mounted a sheet metal sector 2. These sheet metal sectors constitute the fixed part of the circular track.

In the six intervals between the sectors are placed the cylinder-carrying or beam-carrying

2

carriages 4 (Figures 1 and 2) of which five only are shown in Figure 1. These can be displaced radially on rails 3 so as to permit of clearing passages giving access to the interior of the loom for the repair of any derangement (breakage of thread etc.).

These carriages constructed of welded section bars support, at their extremities situated towards the centre of the loom, the cylinders 8 upon which are wound the warp threads 26. They are furnished at their upper part with a sheet metal part 4a which comes level with the sheets of the sectors 2, assuring the continuity of the circular track. Finally, the sectors 2 and the carriages 4 are provided at their outer edges with a guiding means such as a tube 5. Two stools 6 (only one of which is shown in Figures 1 and 2, the second being symmetrically mounted on the rails 3 in Figure 1) are utilized for the surveillance of the shuttle, arrangements for changing bobbins and for the rolling up of the fabric. These stools move upon the platform thus constituted and are guided upon the tube 5 by two wheels 7 mounted on each stool by a fitting 151, which wheels by bearing against one part or another of the tube 5 prevent any swinging.

A carriage 4 is also seen in Figure 11 and a stool 6 in Figure 12.

Each cylinder 8 is constituted by a reel turning about a fixed axis 152 (Figures 1 and 3). Upon each of two flanges 153 of the reel there are mounted two drums 8a used for braking. The fixed axis 152 is mounted in two bearing blocks 24 (Figures 1, 3 and 11) carried by the carriage 4 as previously indicated.

The braking of the cylinder is performed as shown in Figure 3. The brake comprises a detector roller 9 which follows the variation of the external diameter of the cylinder charged with thread, a brake band 10 furnished with friction material, a bent lever 11 articulated at 19 on a fixed point of the frame and connected at 15 by a strap 154 to the band 10, a tension spring 12 attached at 16 to the lever 11 and at 17 to a lever 155a keyed upon the axle 18 of the arm 155 supporting the roller 9, and means for regulating the tension. This latter comprises a lever 13 pivoted at 13a to a fixed mounting 156 solid with the frame of the machine, and a screw 20 which screws in the lever 13 and the extremity 157 of which bears upon the frame. The brake band 10 is attached to the lever 13 by a hook 14 engaging a pin 14a of the lever 13. The spring 12 is always in tension. The arm 155 supporting the detector roller 9 is articulated at 18 to

the frame of the machine. Of course, there is a single detector roller 9 for each beam, but the remainder of the braking device is duplicated, such a device cooperating with each of the brake drums. This results clearly from the symmetrical construction of each beam as a whole.

The detector roller 9 follows the diminution of diameter of the cylinder consequent upon the unwinding of the thread; the point 17 approaches the point 16, thus diminishing the flexure and consequently the tractive effort of the spring 12 upon the lever 11; the latter turns a little about the point 19 and diminishes the tension of the brake band 10 upon the drum 8a of the cylinder. This arrangement which opposes to the unwinding a constant resistance permits of conserving a variable tension for the sheet of warp threads, whatever may be the state of charge of the cylinder. Moreover, it is possible to regulate the tension of the band 10 and consequently to tension more or less the warp threads, by screwing or unscrewing the screw 20 according, on the one hand, to the number of threads utilized in the warp and, on the other hand, the warp count. By screwing the screw 20 downwardly, that is to say, in such a direction that the corresponding end of the lever 13 pivots upwardly about its fulcrum 13a (since the lower end of the screw 20 always bears upon the fixed frame), the pin 14a is lowered, pulling consequently down the hook 14 and the attached end of the band 10. This causes the braking of the cylinder, and consequently results in increasing the tension of the warp threads.

For dismounting the cylinder, the screw 20 is unscrewed to diminish the tension of the band 10 and the lever 11 is swung until its arm 158 bears against a fixed stop 24. The hook 14 can then be disengaged from the pin 14a. Then the arm 155 of the detector 9 can be swung about the point 18. The arm 155 carries a lateral pin 22 which comes into engagement with the extremity 159 of a bent lever 23 pivoted at 160 to the frame and operated by means of a pedal 25 furnished with a restoring spring 25a. A screw 24b is then unscrewed, which screw normally maintains the cap device 24a upon the block 24 and the cap device is swung over.

For re-mounting the cylinder, it is placed upon the bearing blocks 24 of the carriage 4. The cap devices 24a are then turned down and fixed by the screws 24b, and the brake band is reconnected at 14, 14a. The pin 22 of the arm 155 of the detector 9 being already engaged at 159, it suffices to press upon the pedal 25 to liberate the arm 155 and to cause it to restore the detector to its place upon the cylinder. The tension of the brake band is then regulated by means of the screw 20 as indicated above.

On leaving the cylinder, the warp threads 26, which are in the form of a plane sheet, pass into a broken-warp detector arrangement. This is constituted in the following manner (Figure 4):

Each warp thread 26 passes over a first roller 27 then through a hole 28a pierced in a conductive blade 28 which it traverses and finally over a second roller 29. The blades 28 are guided by conductive spacers 28b connected to a box 32. When one of the threads breaks, the blade 28 which it traverses falls upon a conductive plate 30 insulated from the box 32 by a layer 30a. The blade 28, taking a position such as that indicated diagrammatically at 28' by dotted lines, establishes contact between the plate 30 and a wall of the box 32 through the intermediary of 75

the spacers 28b and this closes an electrical circuit represented generally by 31. The walls form a sort of box 32 extending over the whole width of the sheet of threads and a compressed air conduit 33 debouches at the base of the box to blow away fluff which would have a tendency to deposit upon the plate 30 and prevent contact of the blades 28 with the plate. The rollers 27 and 29 are mounted upon the box 32 by supports 27a, 28a.

The closing of the circuit 31 by the fall of a blade 28 releases a safety arrangement 109, for warning or stoppage purposes, which forms no part of the present invention but is, preferably, 15 of the type described in U. S. Patent No. 2,587,982, or in my copending application for U. S. Letters Patent, filed on August 2, 1950, Serial No. 177,281.

After having cleared the second roller 29 of 20 the warp-break detector, the threads 26 should be passed on to the harness and the reed. It is necessary therefore to transform the plane sheet of warp threads into a cylindrical sheet of the same width developed, that is to say such that 25 the threads are equidistantly spaced from one another. In order that these threads shall have no tendency to separate laterally from the ideal line, it is necessary that such line represents the shortest distance measured along the length of 30 the thread between the point of departure from the cylinder and the point of arrival at the eyelet of the heddle which it traverses, or more precisely upon the corresponding point of the interior circle of a curved bar 38 placed in the 35 neighborhood of the eyelets of the heddles 43 and 44 and in front of them (Figures 5 and 12).

Figures 5-10 and 10a show diagrammatically the action of the bar 34 which serves to transform the plane fleece or sheet of warp threads 40 into a cylindrical sheet. This bar has a curvature determined by the following consideration: Let AB (Figure 5) be the line perpendicularly to which the rectilinear distribution of the warp threads is made when they leave the roller 29 45 of the broken-thread detector, that is to say in practice the generatrix along which the threads 26 leave the roller.

These threads should be distributed in the same fashion following the arc A¹B¹ of the interior circumference of the curved bar 38 when 50 developed length is equal to the length of the straight line AB. It will be evident that, without some special arrangement, the thread leaving A will arrive at Z over A¹B¹ (path represented by broken line) following the radius of the arc A¹B¹, that is to say following the shortest path from the point A to the point O situated on the axis of the loom.

For this thread to pass at A¹, it is necessary that it should suffer a deformation which causes it to pass through a point A² situated in an imaginary line xy.

In practice, however, one cannot utilise at A² 65 a conventional system of guidance such as a reed or an eyelet, for this would produce constraint and additional friction, which are causes of thread breakage.

The invention permits of precisely this deficiency to be remedied:

Suppose, for the sake of simplicity, that AB and A¹B¹ are in the same horizontal plane, which can always be provided for in practice, and that an inwardly curved bar 34, whose concavity will be directed upwardly (Figure 6), is 70 disposed at xy.

Referring to Figure 6, it will be seen that the thread 26 is subjected at A² to a pull which is transmitted by two equal, but differently directed, forces F¹, F². These two forces have a resultant R. As R is not perpendicular to the tangent at A²T to the curve xy, that is to say to the line of contact of the threads 26 and the bar 34, there is a component directed along this tangent (Figure 7) to the right or left of the plane of the thread 26. In Figure 7, it will be seen that R, which is not perpendicular to the tangent at A², can be resolved into two forces C¹ and C². The thread 26 passing through A² thus has the tendency to become displaced under the influence of C¹ and in the direction of this force.

As however, on the one hand, A is fixed and, on the other hand, A¹A² is directed towards the center O of the circumference to which pertains the arc A¹B¹ (Figure 5), the plane AA¹A² is determined and, for the component C¹ to be neutralised, it is necessary that this plane should pivot in relation to the plane of the curve xy until the point at which the vector B contained in the plane AA¹A² is perpendicular to the plane of the curve.

There is thus a position of equilibrium, and only one, for the point A² such that the resultant R of the forces applied to the thread 26 is perpendicular to the tangent A² to the curve xy, i. e. a tangent determined by the nature of the said curve.

It will thus be readily appreciated that, if the inclination of the plane of the curve xy to the horizontal plane passing through AB is varied, the threads 26 will slide along the curve xy until they pass through suitable points A².

Numerous experiments have shown that, in practice, the curve xy may be constituted by an arc of a curve of the second order or by a series of arc connected tangentially and belonging to such curves, depending upon the dimensions of the loom and the resistance to the tension of the threads used for the weaving. The bar 34 is thus such that its line of contact with the threads 26 is a curve of the aforesaid type and the correct setting is obtained by inclining to a greater or lesser extent the plane of this line of contact in relation to the horizontal plane passing through AB, that is to say through the generatrix along which the threads 26 leave the bar 29.

In Figure 8, there will be seen at P the horizontal plane passing through AB and at Q the plane containing the curve xy. The angle θ between these two planes can be varied by regulation by means of the mechanism shown in Figures 9, 10 and 10a which permits, by variation of the angle θ , of variation at each point in xy of the slope of the tangent to this curve until it is brought perpendicular to the resultant R of the forces applied to the thread.

In Figures 9, 10 and 10a, there will be seen at 34 the thread-carrying bar which is pivoted at its two ends in spherical bearings 36 secured to the frame 33 of the loom through the intermediary of supports 37.

The regulation of the inclination of the bar 34 is effected by means of a double screw 35 which screws in two rods 40 and 41 the first of which is threaded in one direction and the second in the opposite direction. The rod 40 is connected to the bar 34 by a cover part 42 and the rod 41 is fixed at 43 to the frame 33.

In Figure 9, the bar 34 alone is seen, whilst 75

Figure 10 shows diagrammatically the respective positions of the bars 29, 34 and 38. Figure 10a shows on a larger scale the mounting of one end of the bar 34, through spherical ball bearing 36, on the support 37 carried by the frame 39.

The distribution of the warp threads over an imaginary cylindrical surface effected beyond the bar 38 is thus performed in a purely geometrical fashion and without constraint of any kind. Where they leave the curved bar 38, the threads 26 are passed in known manner into the eyes of the heddles 43 and 44 and thence into the gaps of the reed 103 (Figure 12).

What I claim is:

1. Apparatus for delivering warp threads to a circular weaving loom comprising in combination six beams disposed circularly at the base of the loom along the sides of a regular hexagon and carrying the warp threads, movable carriages supporting the said beams said beams being detachable from said carriages, rails upon which the said carriages move, brake members for each beam, a device termed a "broken-warp detector" across which pass the threads upon leaving the beam, and a thread-supporting bar of predetermined curvature for transforming without constraint the plane surface formed by the warp threads leaving the beam and detector into the cylindrical weaving surface.

2. Apparatus for delivering warp threads to a circular weaving loom comprising in combination beam-carrying carriages, beams carried by these carriages and detachable from said carriages and each of which comprises a flanged cylinder turning about a fixed axle supported in two bearings on the corresponding carriage, brake drums integral with the cylinder flanges, brake bands bearing upon these drums, a cranked lever pivoted on a corresponding carriage and connected to an extremity of the corresponding brake band, a straight lever also pivoted on said corresponding carriage, a spring connecting the extremities of the straight lever and of the corresponding cranked lever, a feeler normally in contact with the thread on the beam and pivoted on the corresponding carriage about the same axis as the straight lever, an arrangement for regulating the tension of each brake band, and means comprising a hook and a pin for temporarily maintaining the feeler away from the cylinder, a broken-warp detector across which pass the warp threads leaving each beam, and a thread-carrying bar for converting without restraint the plane surface of warp threads into the cylindrical weaving surface.

3. Apparatus for delivering warp threads to a circular weaving loom comprising in combination a frame constituted by six I-bars disposed radially at the base of the loom, sheet-metal sectors mounted upon these bars, rails disposed radially between each sector, and an annular guiding member surrounding the platform formed by these sheets, beam supporting carriages moving upon the said rails and having sheets in the same horizontal plane as the sector sheets, beams detachably supported by the carriages and carrying the warp threads, braking members for each beam, a broken-warp detector disposed where the threads leave each beam, and a thread-carrying bar for converting without restraint the plane surface of the warp threads into the cylindrical weaving surface.

4. Apparatus of delivering warp threads to a circular weaving loom, comprising in combination beams carrying the warp threads, a broken-

warp detector constituted by two rectilinear bars over which pass the warp threads and having between them parallel conducting blades pierced with holes for the passage of the warp threads, a box, also conducting, supporting the bars and containing the blades, spacing members, for the blades, also conducting and connected to the box, a conducting base plate insulated in relation to the box, and an electrical circuit comprising an alarm device, a source of current, the box and the spacing members on the one hand and the base plate on the other hand, and a thread-carrying bar for converting without constraint the plane surface of the warp threads into the cylindrical weaving surface.

5. Apparatus for delivering warp threads to a circular weaving loom, comprising in combination beams carrying the warp threads, broken-warp detectors disposed when the threads leave these beams, a curved horizontal bar the internal generatrix of which determines the cylindrical weaving surface, thread-carrying bars whose line of contact with the warp threads is

constituted, for each beam by a curve of the second order or by several successive arcs of such curves, and means for varying, for regulation purposes, the inclination of the thread-carrying bars and comprising a double screw mounted upon two threaded rods the first of which is threaded in one direction and the second in the opposite direction and fixed one to the frame of the loom and the other to the middle of the thread-carrying bar, this latter bearing at its extremities against two spherical bearings.
